VIBRATING TRACER STYLUS

Lawrence Edgar Marchant, Toronto, Ontario,
Canada, assignor to A. V. Roe Canada Limited,
Malton, Ontario, Canada, a corporation

Application November 3, 1949, Serial No. 125,204

7 Claims. (Cl. 33—23)

1

This invention relates generally to tracing stylus for duplicating machines, and more particularly to means for rapidly vibrating a stylus in order to reduce the effects of friction between the stylus and a pattern over which it moves.

Generally speaking, in mechanical duplicating machines, a movable work table mounted on a frame supports a pattern of the contour to be reproduced and a blank in which the contour is to be reproduced. Adjacent to the model is mounted a tracing stylus or follower, and adjacent to the blank is mounted a power-driven cutting head. The stylus and cutting head are fixed relatively to each other, or are arranged so that the movement of the cutting head will be proportional to the movement of the stylus. Usually the work table is provided with driving means that move the table in its own plane in two directions at right angles to each other, the work table being usually reciprocated in one direction and indexed or moved by small increments in the other direction.

It has been found that vibrations induced in a stylus enable it to move more freely over the pattern contour, thus enabling the cutting head to reproduce in the blank more faithful copies of the pattern contour. It has also been found that the vibrations induced in the stylus should preferably be rapid but of comparatively small amplitude.

It is therefore an object of the invention to provide in a stylus a vibrating device which produces rapid low-amplitude vibrations.

A further object of the invention is to provide a stylus vibrating device which may conveniently be applied to conventional duplicating machines.

All of the foregoing and still further objects and advantages of the invention will become apparent from a study of the following specification, taken in conjunction with the accompanying drawings, wherein like characters of reference indicate corresponding parts throughout the several views and wherein:

Fig. 1 is a broken away perspective view of a tracer stylus embodying the invention; and

Fig. 2 is a perspective view of a tracer stylus embodying an alternative form of the invention.

Referring to Fig. 1, an ordinary stylus holder 3 is provided with a collet type locking nut 4 which clamps the shank of a stylus 5, the free end 5a of the stylus being adapted to bear against a pattern 6. Suitably secured to the stylus immediately below the locking nut is a collar 7 having an upper internal flange 7a and a lower internal flange 7b which define an annular cham-

2

ber 8. An inlet pipe 9 which extends through the collar into the chamber 8 is adapted to be connected by a length of flexible tubing 10 to a supply of fluid under pressure, preferably compressed air.

The internal periphery of the upper flange 7a of the collar makes a substantially air-tight joint with the stylus 5 whereas there is provided in the internal periphery of the lower flange 7b of the collar a helical groove 7c which is essentially a coarse thread. The crests of the thread engage the stylus, the thread grooves thus forming a helical conduit connecting the chamber 8 to the space below the lower flange 7b.

15 Concentrically mounted below the collar 7 and spaced therefrom is a cup-like member 11 which provides a race 12 in which a small steel ball 13 is free to roll in a circular path around the stylus 5. The diameter of the ball should be substantially greater than the space or gap between the collar 7 and the cup-like member 11.

In operation, high pressure air is admitted to the chamber 8 through the inlet pipe 9 and the flexible tubing 10. In order to escape from the chamber 8, the air travels downwardly through the helical conduit provided by the groove 7c, which imparts a rapid whirling motion to the air and discharges it into the race 12 where it causes the steel ball 13 to rotate rapidly around the stylus 5. The air is finally exhausted to atmosphere through the gap between the collar 7 and the cup-like member 11.

The rotation of the ball 13 around the stylus 5 produces an unbalance in the stylus of a frequency proportional to the speed of rotation of the ball around the stylus and an amplitude proportional to the weight of the ball and to the diameter of the race. The vibrations thereby induced in the stylus cause variations in the pressure of the stylus against the pattern 6, which variations in pressure tend to relieve the frictional drag of the stylus against the pattern, and prevent the stylus from sticking and advancing with a jerky motion.

45 In an alternative embodiment of the invention illustrated in Fig. 2, a small elementary turbine rotor 14 is rotatably mounted on a stylus 15 shown bearing against a pattern 16, by means of a ball bearing member 17, the inner race of which is pressed onto the stylus. The turbine wheel is deliberately unbalanced by removing a small amount of metal at one point or by other means well known in the art. High pressure air from a nozzle 18 impinges tangentially against the turbine wheel; this causes the turbine wheel to

rotate at a high speed, and because of the unbalance in the turbine wheel vibrations of a frequency proportional to the speed of rotation of the wheel and of an amplitude proportional to the static unbalance in the wheel are set up in the stylus 15, as in the preferred embodiment of the invention.

With either embodiment of the invention, the frequency of the vibrations may be varied at will by providing a suitable throttle in the compressed air supply; in order to avoid resonant effects it is desirable to avoid vibrating the tracer stylus at any frequency which is a multiple of the frequency at which the cutter teeth engage the blank. The amplitude of the vibrations may be varied by changing the radius of rotation of the rotating unbalanced mass or by changing the magnitude of the unbalance.

It is thought that the construction and use of the invention will be apparent from the above description of the various parts and their purpose. It is to be understood that the form of the invention herewith shown and described is to be taken as a preferred example of the same and that various changes in the shape, size and arrangement of parts may be resorted to, without departing from the spirit of the invention or the scope of the subjoined claims.

What I claim as my invention is:

What I claim as my invention is:

1. In a tracer having a stylus adapted to bear against a pattern, means for vibrating the stylus comprising a mass rotatably mounted on the stylus and unbalanced about its centre of rotation, and means for rotating said mass.

2. In a tracer having a stylus adapted to bear against a pattern, means for vibrating the stylus comprising a mass rotatably mounted on the stylus and unbalanced about its centre of rotation, and means for rotating the mass including a nozzle arranged to direct a flow of fluid which impinges on the rotatable mass eccentrically of its centre of rotation.

3. In a tracer having a stylus adapted to bear against a pattern, means for vibrating the stylus

comprising an endless race mounted on the stylus, a rollable body adapted to travel in the race, and means for causing the rollable body to travel in the race, including a nozzle arranged to direct a flow of fluid on the rollable body.

- 5 flow of fluid on the rollable body.

4. In a tracer having a stylus adapted to bear against a pattern, means for vibrating the stylus comprising an annular race mounted on the stylus and having the stylus as its centre, a rollable body adapted to travel in the race, and means for causing the rollable body to travel in the race, including a collar mounted on the stylus adjacent the race, a conduit in the collar having one end connected to a supply of fluid under pressure and its other end being open and directed in the race to eject a flow of fluid which impinges on the rollable body.

10 5. In a tracer having a stylus adapted to bear against a pattern, means for vibrating the stylus comprising an annular race mounted on the stylus and having the stylus as its centre, a rollable body adapted to travel in the race, and means for causing the rollable body to travel in the race, including a collar mounted on the stylus adjacent the race, a chamber in the collar and connected to a supply of fluid under pressure, a helical conduit in the collar coiled around the stylus and having one end connected to the chamber and its other end opening into the race for directing a flow of fluid into the race to roll the rollable body in the race around the stylus.

20 30 6. In a tracer having a stylus adapted to bear against a pattern, means for vibrating the stylus comprising an unbalanced wheel mounted on the stylus and means for rotating the wheel about the stylus.

35 7. In a tracer having a stylus adapted to bear against a pattern, means for vibrating the stylus comprising a turbine wheel rotatably mounted on the stylus which provides its axis of rotation, and a nozzle arranged to direct a flow of fluid on the wheel to rotate it about the stylus.
